SPRAY ATTACHMENT FOR VACUUM CLEANERS

Council A. Tucker, Glendale, Calif., assignor to Interstate Precision Products Corporation, Anaheim, Calif., a corporation of California

Application May 22, 1956, Serial No. 41,592

Term of patent 7 years

(Cl. D9—2)

FIG. 1.

FIG. 2.

FIG. 3.

FIG. 4.

Fig. 1 is a view in side elevation of the spray attachment for vacuum cleaners embodying my new design;
Fig. 2 is an end view of the same;
Fig. 3 is an end view of the same taken from the opposite end from that on which Fig. 2 is taken; and
Fig. 4 is a top plan view of the same.

I claim:

The ornamental design for a spray attachment for vacuum cleaners, as shown.
